LAWN SPRINKLER

John D. Beinert, Babylon, N.Y., assignor to International Patent Research Corp., 70 Milton Friedman, Esq., New York, N.Y., a corporation of New York

Filed Apr. 21, 1966, Ser. No. 1,959

Term of patent 7 years

(Cl. D91—1)

FIG. 1

FIG. 2

FIG. 3

FIG. 4

FIG.5

FIG.6

FIG. 1 is a three-quarter perspective view of a lawn sprinkler, showing my design;

FIG. 2 is an end elevational view of the lawn sprinkler on an enlarged scale, taken from the right hand end of FIG. 1;

FIG. 3 is a side elevational view of the device of FIG. 1;

FIG. 4 is a top elevational view thereof;

FIG. 5 is a bottom elevational view thereof; and

FIG. 6 is an end elevational view on an enlarged scale of the lawn sprinkler of FIG. 5, taken along the line 6—6 of FIG. 5.

The dominant portions of my new design are those shown in solid lines.

I claim:

The ornamental design for a lawn sprinkler, as shown and described.
